UNITED STATES PATENT OFFICE.

JACOB DE STEFANO, OF KANSAS CITY, MISSOURI, ASSIGNOR OF ONE-HALF TO PETE RAPPAS, OF KANSAS CITY, MISSOURI.

LIFE-SAVING DEVICE FOR SUBMARINES.

Application filed April 4, 1921. Serial No. 458,235.

To all whom it may concern:

Be it known that I, JACOB DE STEFANO, a subject of the King of Italy, and a resident of Kansas City, county of Jackson and State of Missouri, have invented a certain new and useful Improvement in Life-Saving Devices for Submarines, of which the following is a complete specification.

This invention relates to life saving apparatus for use on submarines and vessels of practically any description, and has for its object to produce a device whereby the entire crew of a submarine may escape should the vessel become unmanageable through accident and commence to sink, or rest submerged and be unable to rise to the surface of the water.

Another object is to produce a device of this character wherein the persons enclosed may be protected from the elements and which will float on the surface for an indefinite period of time without danger to such occupants.

With these general objects in view the invention consists in certain novel and peculiar features of construction and organization of parts as hereinafter described and claimed; and in order that it may be fully understood, reference is to be had to the accompanying drawings, in which:

Figure 1 is a side elevation of a submarine equipped with two of the devices of the invention, it being understood that the relative sizes of the submarine and life saving device are out of proportion, to more clearly illustrate the invention.

Figure 2, is a side elevation of the device as it will appear when released and floating on the surface of the water.

Figure 3, is a central vertical section of the device and connections for fastening it to the submarine.

Figure 4, is a top plan view, partly broken away to illustrate the interior of the device and the release mechanism at the bottom thereof.

In the said drawings, where like reference characters identify corresponding parts in all of the figures, 1 is a submarine of conventional design and character and equipped with two of the life saving devices of the invention 2, which are constructed of metal of sufficient thickness to withstand all water pressures to which the submarine will be

subjected and which are provided with windows 3, a guard or cage 4 to protect the door 5 of a manhole from floating objects in a rough sea. The door 5 is equipped with hinges 6 for an object hereinafter mentioned.

To one side of the device and outside of the guard or cage 4, is a vertical air tube or vent 7, equipped at its upper end with cross tubes 8, which are provided with flared mouths 9 facing in opposite directions for the purpose of aiding in the ventilation of the device when it is floating on the surface of the water. The top of the air vent 7 is provided with an electric lamp 10 which functions as a signal lamp at night and which may have any suitable connections (not shown) with a source of energy in the interior of the device. Within the device the lower end of tube 7 is provided with a branch portion 11 extending to the exterior of the device just above the water level; the tube 7 and its branch 11 being provided with hand valves 12 and 13 respectively, within the life saving device for a purpose which will hereinafter appear.

On the inner side of the hinged cover 5 is a groove 14 into which a metal gasket 15 snugly fits to prevent the entry of water when the device is submerged; and at its center is provided with a reinforcement 16 to which is secured a stud bolt 17 extending into the life saving device and upon which is slidably mounted a cross piece 18 engaging the inner side of the deck 19 of the device. Against the clamping cross piece 18, a band wheel 20 is provided for securely clamping the cover 5 against the circular flange 21 on the upper face of the deck 19 and thus compresses the gasket and prevents the entry of water into the device, either when it is submerged or when floating on the surface of the water during rough weather when it will be necessary to close the door.

The lower part of the device is provided with a circular floor 22 and depending from the inner margin of said floor is an inverted dome 23, provided on its exterior walls at diametrically opposite points with radial fins 23^a for preventing the device from revolving on its own axis when floating in the water. The dome-shaped portion 23 is of such size as to fit into an inverted dome-shaped cage 24 securely fastened to the inner wall of a submarine at 25; the deck of

the submarine being cut away as at 26 to provide a slightly larger opening than the diameter of the dome 23 for the accommodation of the latter. The floor 22 of the device 5 is adapted to abut a gasket 27 on the upper face of the deck of the submarine to establish a water tight joint therewith and also forms the floor of the device, under ordinary conditions, and a circular bench 28 may be fastened to the interior wall at a suitable distance 10 from the floor for the accommodation of the passengers contained therein.

At a suitable distance from the bottom of the dome 23 a floor 28^a is provided and between 15 this floor and the bottom of the dome, lead, or any other suitable ballast 29, is placed in order to keep the device upright when it is released from the submarine and is floating on the surface of the water. A 20 bushing 30 extends through openings in the floor, the ballast and the dome and is provided at its upper end with a stuffing box 31 and at its lower end engages a collar 32 secured on a bolt 33 equipped at its upper 25 end with a hand wheel 34 and at its lower end is suitably threaded for engagement with a threaded opening in a cross piece 35 spaced a suitable distance from the bottom of the dome 24 of the submarine for a purpose 30 hereinafter described.

At a predetermined point in the wall of the dome 23 is a manually operable door 36 adapted to turn on hinge 37 and provided with a bolt 38 threaded on its inner end and 35 engaged by a hand wheel 39 for engagement with a cross piece 40 abutting the inner side of the wall of the dome. The action of the hand wheel will firmly clamp the edge of the door against a gasket 41 fitted around the 40 periphery of the former. At a diametrically opposite point, but in the inverted-dome 24 of the submarine is a similar door 42, provided with a hinge 43, stud bolt 44, hand wheel 45, cross piece 46 and gasket 47, the 45 wheel being so situated that it may be operated from the interior of the dome of the life saving device and thus prevent the entry of water into the submarine upon the release of such device. As it may be desirable 50 in calm weather to open the door 5 for the better ventilation of the device and to enable the occupants of the device to easily reach the deck 19 for signaling purposes and also for escape should a boat approach to pick 55 them up, a ladder 48 has been provided.

When the submarine is in normal working condition, the communicating doors 38 and 42 will stand open to allow a free circulation of air between the buoyant device and 60 the submarine, and the valve 13 of the buoyant device will also normally stand in open position, for a purpose which hereinafter appears; and the door 5 and the valve 12 are closed to prevent the entrance of 65 water into the device and submarine, and the

threaded releasing bolt 33 is engaged in the cross piece 35, as shown clearly in Figure 3, to maintain the device attached to the exterior of the submarine, and thus provide for the free circulation of air in the submarine and device, the gasket 27 maintaining a water tight joint between the two members. It will be understood that when submerged, water is free to enter air tubes 7 and 11, but cannot enter the device as the valve 12 will remain closed at this time. It will be understood also that this life saving device may be made in various shapes and sizes and that there may be an indeterminate number of such devices secured to the deck 75 of a vessel, depending upon the number of passengers contained therein.

Should an accident occur to the machinery of the submarine while the latter is submerged, the crew will enter the life saving 85 device and will close doors 42 and 36 and fasten them securely in position by means of the hand wheels 45 and 39. Hand wheel 34 will then be operated and through the upward pressure of collar 32 on the lower end 90 of the device, will raise the latter should it have a tendency to adhere to the gasket 27 from any cause. This action permits water to enter the inverted dome 24 through the opening 26, such water being excluded from 95 the interior of the submarine by the closed door 42 and from the interior of the device by the closed door 36. The continued operation of hand wheel 34 will release bolt 33 from engagement with the cross piece 35 of the dome 100 of the submarine. The instant the life saving device is released from engagement with the submarine, it will, through its buoyancy, rise to the surface of the water. Upon the emergence of the upper part of the device 105 above the surface, the water contained in tube 7 will drain out through branch 11, valve 13 will then be closed and valve 12 opened to provide for the ventilation of the interior of the device, it being understood 110 that in calm weather, the door 5 may be opened for the better ventilation of the device.

It will also be understood that the device may be fitted to the submarine without the necessity of providing the latter with the dome 24, but, of course, in this instance, water will be free to enter the submarine the instant the floor 22 is unseated from the gasket 27, and also that the device may be 120 made of any suitable or preferred shape and dimensions.

From the above description, it will be apparent that I have produced a device of the character described, which possesses all of 125 the features of advantage pointed out as desirable in the statement of the object of the invention and while I have described and illustrated the preferred embodiment of the same, I reserve the right to all changes 130

properly falling within the spirit and scope of the appended claim.

I claim:

The combination with a vessel, of a buoyant device detachably secured to said vessel, 5 a vent in the upper part of the device, a valve controlling said vent and operable

from within said device, and a valve-controlled drain tube extending from said vent above the valve thereof to the exterior of 10 said buoyant device.

In testimony whereof, I hereunto affix my signature.

JACOB DE STEFANO.
